(57) **CLAIM**

The ornamental design for an insert for a case for holding a blister pack, as shown and described.

DESCRIPTION

FIG. 1 is a top perspective view of an insert for a case for holding a blister pack, showing our new design;

FIG. 2 is a top perspective view of the insert for a case for holding a blister pack, shown removed from the case.

FIG. 3 is a bottom perspective view thereof;

FIG. 4 is a left side view thereof;

FIG. 5 is a right side view thereof;

FIG. 6 is a front view thereof;

FIG. 7 is a rear view thereof;

FIG. 8 is a top view of the insert for a case for holding a blister pack, shown inside the case; and,

FIG. 9 is a bottom view of the insert for a case for holding a blister pack, shown removed from the case.

The dashed broken lines depict portions of the article that form no part of the claimed design; the dash-dot-dash broken lines depict environment that forms no part of the claimed design.
